CLAIM

The ornamental design for a quadruped robot as shown and described.

DESCRIPTION

FIG. 1 is a perspective view of a quadruped robot showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of encircled portion 9 in FIG. 1;

FIG. 10 is an enlarged detail view of encircled portion 10 in FIG. 1; and,

FIG. 11 is an enlarged detail view of encircled portion 11 in FIG. 4.

The dot-dot-dash lines used in FIG. 1 indicate the portions being enlarged in FIG. 9 and FIG. 10. The dot-dot-dash lines used in FIG. 4 indicate the portion being enlarged in FIG. 11.

1 Claim, 11 Drawing Sheets
